FIG. 1

FIG. 2

FIG. 3

FIG. 1 is a front perspective view of design of the invention as embodied in a canoe, taken from above and slightly at one side of the canoe;

FIG. 2, a front perspective view, taken from slightly below and to one side;

FIG. 3, a similar rear perspective view;

FIG. 4, a top plan view; and

FIG. 5, a side elevation view, the other side being a mirror image thereof.

The characteristic features of my design reside in the overall features as shown in FIG. 1, particularly in combination with the specific configuration of the combined gunnel and seat-thwarts, and the filled and sloped and curved fore and aft compartments as best seen in FIG. 4.

I claim:

The ornamental design for a canoe, substantially as shown and described.
